UNITED STATES PATENT OFFICE.

ENOCH OHNSTRAND, OF MOHAWK, NEW YORK, ASSIGNOR TO LIBRARY BUREAU, OF
CAMBRIDGE, MASSACHUSETTS, A CORPORATION OF NEW JERSEY.

LABEL-HOLDER.

1,376,725.

Specification of Letters Patent.

Patented May 3, 1921.

Application filed May 4, 1920. Serial No. 378,828.

To all whom it may concern:

Be it known that I, ENOCH OHNSTRAND, a citizen of the United States of America, and resident of Mohawk, in the county of 5 Herkimer and State of New York, have invented new and useful Improvements in Label-Holders, of which the following is a specification.

My invention consists in improved means 10 for providing shelf boards and the like with label plates, the object being to dispense with screw or nail fastenings through the label plate and into the front edge of the shelf board, to apply the label plate to the front 15 edge of the shelf board more securely and permanently than is possible by the use of nail fastenings, to eliminate all projecting parts, associated with the label plate, such as clip-members, from the upper or supporting surface of the shelf board, to reduce to 20 a minimum the projection of clip-members and the like from the lower side of the shelf board, and to provide, nevertheless, a label plate which can be quickly and readily attached or detached from the shelf board, 25 leaving it free from any visible blemishes.

Heretofore, so far as I am aware, label plates have been attached to the wooden shelf-boards of bookcases and the like, either 30 by means of small nails, such as scutcheon pins, or have been provided with resilient pins, or have been provided with resilient clips which embrace the shelf board at top and bottom. Nail fastenings, and even screw fastenings, for label plates are notoriously insecure; they loosen whenever the wood, of which the shelf board is composed, shrinks; and where once so loosened cannot with any certainty be again made secure. Moreover, a nail fastened label plate cannot 35 be shifted to another position (as is often necessary) without leaving the nail holes as a visible disfigurement on the exposed edge of the shelf board.

The use of any clip members which lie on 40 the upper surface of a shelf board is undesirable, since it involves an obstruction to the insertion or removal of books and the like, and is liable to be displaced by such normal use of the shelf.

By means of my improvement, herein described, a label plate and means for attaching it to a shelf board are provided which eliminate the above mentioned disadvantages, and which combine facility of attachment with security of lodgment, without 45

involving any noticeable alteration in the surface of the shelf board.

In the drawings hereto annexed, which illustrate my invention—

Figure 1 is a front elevation, showing 60 part of a wooden shelf board, with label plate attached.

Fig. 2 is a rear elevation of the label plate.

Fig. 3 is an end elevation of the label plate, and 65

Fig. 4 is a vertical cross section of the shelf board and label plate, at the line 4—4 of Fig. 1.

In these drawings, 1 represents an ordinary wooden shelf board. The means on the 70 shelf board for providing securement of the label plate consist simply of a groove or kerf, 2, cut in the lower side of the shelf board a short distance from, and parallel with, the front edge of the board. This 75 kerf, which will preferably be cut by a circular saw, is hardly visible when the shelf board is in use, and if noticed, is in a sense unsightly.

The label plate, 3, preferably made of thin 80 metal, has its upper and lower edges and one end edge turned over as at 4, 4, and 5 in the usual manner, to provide a holder for the label 12; if desired a projection 6 may be struck up from the face of the plate 3, to 85 serve as a stop for the label 12.

The holding clip is a plate of resilient material, such as steel or hard brass, preferably as thin as is consistent with the strength required, and having a portion 7 90 which is fastened to the label plate 3 at the back thereof, a flat portion 8, and a spring tongue 9, terminating in a reverse curve at the lip 10. The securement of the holding clip to the plate will preferably be by means 95 of spot-welds, as at 13 (Fig. 2).

The proportions of the holding clip are such that when the spring tongue 9 is inserted in the kerf 2, it will be flexed, so as to draw the portion 7 of the clip closely 100 against the front edge of the shelf board. The tongue 9 is guided into the kerf 2, and its flexure readily accomplished by the action of the lip 10. In attaching the label plate by the above described means, the tongue 9, 105 is pressed into the kerf 2 until the flat portion 8 of the clip bears snugly against the lower side of the shelf board 1. It will be observed that no part of the attached members lies above the plane of the upper 110

side of the shelf board, and that the projection below the shelf board is reduced to the negligible thickness of the spring clip portion 8. Even if a book or other article, on being removed from the shelf below, should strike against the inner corner of the spring clip, it could in no wise disarrange or dislodge the clip and label plate attached thereto; these attached members must be 5 pressed downwardly in order to be detached; no conceivable use or misuse of the shelves or their contents can exert such downward pressure on the clip or label plate.

Usually it will be desirable to rely wholly 10 on the frictional engagement of the plate holding clip with the side of the kerf 2, and this frictional engagement will, no doubt suffice to hold the label plate in the 15 position where it has been placed. If however, further insurance against displacement is desired, a short nail 11 can be driven 20 through the flat part 8 of the spring clip into the lower side of the shelf board, where the nail hole will not be conspicuous after 25 the label plate has been removed. The use of such a nail fastening is not believed to be necessary in any case.

The ease with which the above described 30 means for attaching labels to shelf boards can be manipulated either for attachment or detachment, or for lateral shifting on a shelf board without detachment, is obvious 35 without further description.

I claim:—

35 1. The combination of a shelf-board, having a kerf cut in the body thereof on the underside, parallel with, and near the front edge of the shelf board, and a label plate 40 adapted to lie against the front edge of the shelf board and a securing clip, attached

to the label plate and comprising a flat portion adapted to lie against the bottom of the shelf board between the front edge thereof and said kerf, and a resilient tongue adapted to enter the said kerf and frictionally 45 engage the side thereof toward the front of the shelf board by resiliently pinching against said front side of said kerf.

2. The combination of a shelf-board, having a kerf cut in the body thereof on the 50 underside, parallel with and near the front edge of the shelf-board, and a label plate adapted to lie against the front edge of the shelf-board, and a securing clip, attached to the label plate and comprising a flat 55 portion adapted to lie against the bottom of the shelf-board between the front edge thereof and said kerf, and a resilient tongue adapted to enter the said kerf by movement transverse thereto and frictionally engage 60 the side thereof toward the front edge of the shelf-board.

3. The combination of a shelf-board, having a kerf cut in the body thereof on the under side, parallel with and near the front 65 edge of the shelf-board, and a label plate adapted to lie against the front edge of the shelf-board, and a securing clip attached to the label plate and comprising a flat portion wholly below the lower edge of the 70 label plate, adapted to lie against the bottom of the shelf-board between the front edge thereof and said kerf, and a resilient tongue adapted to enter the said kerf and frictionally engage the side thereof toward the front 75 of the shelf-board, by resiliently pinching against said front side of said kerf.

Signed by me at Ilion, New York, this 29th day of April, 1920.

ENOCH OHNSTREND.
